(57) **CLAIM**

The ornamental design for an off road vehicle roof extension as shown and described.

DESCRIPTION

FIG. 1 is perspective view of an off road vehicle roof extension, showing an embodiment of my new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof;

FIG. 7 is a rear view thereof;

FIG. 8 is a perspective view of an off road vehicle roof extension, showing another embodiment of my new design, which is a mirror image of the roof extension shown in FIGS. 1-7;

FIG. 9 is a top plan view thereof;

FIG. 10 is a bottom plan view thereof;

FIG. 11 is a left side view thereof;

FIG. 12 is a right side view thereof;

FIG. 13 is a front view thereof;

FIG. 14 is a rear view thereof;

FIG. 15 is a front perspective view of the off road vehicle roof extension of FIGS. 1-7 shown installed in an unclaimed environment of an off road vehicle; and,

FIG. 16 is a close up perspective view of the off road vehicle roof extension of FIGS. 8-14 shown installed in the unclaimed environment of the off road vehicle.

The figures show broken lines that do not form any part of the claimed design. The broken lines immediately adjacent the solid line portions of the design form the boundary of the design, with the broken lines forming no part of the claimed design.
